UNITED STATES PATENT OFFICE

DONALD E. CLARK, OF SANTA MONICA, CALIFORNIA

SELF-PLAYER FOR PIPE ORGANS

Application filed September 25, 1928. Serial No. 308,221.

My invention relates to self-players for pipe organs, and more particularly to certain improvements by means of which I am able to control from the usual perforated record of standard piano roll width, not only the pedal and manual notes, but the individual manipulation of eighty-five or more stop tablets.

In present player records, within the note range, whether for piano or organ, each perforation performs a single function only.

With my invention, I am able to cause these same perforations to perform one or more additional functions, thus making it possible, by means of additional perforations in a roll of standard width and perforation, and which can be made by present perforating machinery, to control and manipulate an organ in the same manner that an organist does, including the operation of swell shutters, pulling and cancelling of individual stops and toe pistons, and playing one or all of three manuals, or the main pedal section and the echo organ pedal section.

Thus with a minimum of additional means or mechanism, I am able to control and manipulate the various control devices of a pipe organ from a standard roll.

In order to fully explain my invention, I have illustrated on the accompanying drawings sufficient mechanism to embody my invention, which I will now describe.

Figure 1 is a diagrammatic view showing the control mechanisms and their various connections electrically and pneumatically;

Figure 2 is a plan view of shutter operating mechanism;

Figure 3 is an end view thereof;

Figure 4 is a sectional view taken on line 4-4 of Fig. 3;

Figure 5 is an enlarged view of the stop tablets, usually manually operated;

Figure 6 is a front view of the manuals and foot pedals of an organ related to a tracker bar, over which the perforated music sheet moves;

Figure 7 is a plan view, on an enlarged scale of a pneumatic switch control from the tracker bar, also showing the music roll over said tracker bar;

Figure 8 is a vertical sectional view therethrough on line 8-8 of Fig. 7;

Figure 9 is an enlarged, vertical sectional view of one of the electrically controlled pneumatic switch bar operating devices;

Figure 10 is an end elevation of the same, from the left hand side of Fig. 9, with parts broken away;

Figure 11 is an enlarged edge view of an armature valve member, partly in section;

Figure 12 is a fragmentary portion of a music roll showing how, with my invention applied thereto, a regular note playing hole therein can be made to perform a variety of different functions;

Figure 13 is a fragmentary section of a standard music roll for piano showing how my additional holes can be placed therein for automatically operating the stop tablets suitable for the music to immediately follow on said roll;

Figure 14 is a similar view showing a specially prepared music roll and illustrating how the stop tablets can be operated in one section, for one manual, while notes are being played from another section on another manual.

I have shown so much of an electrically operated pipe organ as is necessary to illustrate how my invention can be attached thereto for the purpose of causing the various controls to be automatically operated instead of manually operated, such operation being controlled from the standard piano roll width of record, a few additional perforations being required in said perforated music roll. It makes possible the use of any standard eighty-eight note music roll, such as are now for sale and which were originally designed to be played on self player pianos, for self player for pipe organs.

Referring now more in detail to the drawings, Fig. 6, 11 designates the usual tracker bar 12, 13 and 14 designate a three manual console, and 15 designates the pedals. The tracker bar 11 is shown divided into three sections, indicated by the brackets 16, 17 and 18, representing the normal corresponding playing positions of each section, indicated by the light lines running therefrom to the

manuals, while the light broken lines running from said tracker bar to said manuals indicate the keys which can be made to play by use of the additional holes in the tracker bar and paper roll beyond the ordinary note playing range. I have shown eight additional holes at each of the opposite ends of said tracker bar, said holes constituting expression holes and they are designated 19, 20, 21, 22, 23, 24, 25 and 26, on the right hand end of said tracker bar, and 27, 28, 29, 30, 31, 32, 33 and 34, on the left hand end of said tracker bar.

Referring now to Fig. 1, I have shown a portion of section 18 of said tracker bar 11, including holes 19, 20, 21 and 22, and also a portion of section 16 of said tracker bar, including holes 37 to 42, inclusive, which are note playing holes, and also a portion of the left hand end of said tracker bar, including holes 28 and 29. My invention includes the additional holes 19 to 26, inclusive, and the holes 27 to 34, inclusive, in the opposite ends of the tracker bar, which are in addition to the note playing holes included in sections 16, 17 and 18 of said tracker bar. These additional holes are provided for the purpose of operating the expression controlling mechanisms, which are usually manually operated. These expression holes 19 to 26 and 27 to 34, with the exception of holes 28 and 29, cause the note playing holes of sections 16, 17 and 18, to perform various additional functions, as hereinafter described.

Each of said tracker bar holes is connected by means of a rubber tube, as 35, to a pouch box 44, shown in enlarged cross sectional view in Fig. 8. Said pouch box is old in the art and is connected with means (not shown) for maintaining therein a partial vacuum. There is also provided therein two switch contact members 45 and 46, the member 46 being adapted to be moved by a flexible diaphragm 47, over an air pocket 48, connected directly to the tube 35, through the passageway 49, which passageway has a vent or bleed 50. Said contact members 45 and 46 are connected through wires 45' and 46' into an operating circuit from a generator 53. The usual perforated music sheet is designated as a whole 51, and is wound on the rollers R and R'.

Inasmuch as a partial vacuum exists in said pouch box 44, it will be understood that when a hole of the perforated music sheet registers with a hole in the tracker bar, that free air enters through tube 35 and passageway 49 to the air pocket 48, thereby lifting the diaphragm 47 and closing the switch members 45 and 46, thus establishing a circuit therethrough. When the hole in the tracker bar is again closed, the air in the air pocket 48 escapes through passage 49 and bleed 50, into pouch box 44 under the vacuum tendency existing therein, causing the diaphragm 47

to drop and the switch member 46 to move away from switch member 45.

The lower switch member 46, in each case, is connected with the generator 53 through its wire 46'. The switch members controlled through holes 19, 20, 21 and 22, are connected by wires 19', 20', 21' and 22' into a circuit 52, which extends to a contact member 54, cooperating with a contact member 54', from which extends circuit 55, running to the generator brush 56. The switch members controlled by the holes 37 to 42, inclusive, are connected directly to said brush 56, by the circuit wires all designated 57. The upper switch members 45, for the holes 19, 20, 21 and 22, are connected by circuits 19'', 20'', 21'' and 22'', to four electric control pneumatics 58, 59, 60 and 61, an enlarged detail of which is shown in Fig. 9. Each of these devices includes a box or air chest 61^a, the bellows 61^b, connected by a port 61^c. The air chest 61^a is supplied with air under pressure through pipe 62, from the organ blower, not shown. A double valve 63 is connected with the flexible diaphragm 63', over a pocket 64, with passageway 65 to the air chamber 66. Said double valve controls the air from said air chest through the port 61^c to the bellows and from the bellows to the atmosphere. Said double valve 63 is controlled by a magnet 67. When energized, said magnet attracts armature 68 (shown in enlarged view in Fig. 11), closing the port 69 and opening a port 70, from the air chamber 66 and passageway 65 to the outside atmosphere. Thus, when said magnet 67 is energized and port 70 is opened, the air pressure operates to move the diaphragm 63' and lifts the double valve 63, permitting air under pressure to pass into the bellows 61^b, forcing them outwardly, as indicated in the light broken lines, thereby operating a pull rod 71. When said magnet is deenergized, its armature valve 68 is forced outwardly by the air pressure from port 69 until it closes port 70, thereby equalizing the pressure in the passageway 65 and the air chest 61^a and allowing the valve 63 to be closed by pressure from within said air chest, and permitting the air from the bellows 61^b to escape to the atmosphere.

The switch members 45, in pouch box 44, controlled by the tracker bar holes 37 to 42, inclusive, are connected by wires 37', 38', 39', 40', 41' and 42', to corresponding, fixed contact bars 72, 73, 74, 75, 76, 77, 78 and 79, inclusive, as clearly shown in Fig. 1. Movable switch bars, of insulating material, and designated, respectively, 80, 81, 82, 83, 84, 85, 86 and 87, are provided. Switch bar 80 is provided with a series of contact elements 80', on its upper side, and with contact elements 80^a, 80^b, 80^c and 80^d on its under side. Movable switch bars 81, 82, 83, 84, 85, 86 and 87 are each provided with a series of contact elements, as 81', 82', 83', 84', 85', 86' and 87'. 130

Switch bar 86 is also provided on its upper side with four circuit breakers, as 86^a, in circuits 88, 89, 90 and 91, extending from the contact elements 80^a, 80^b, 80^c and 80^d, respectively, to controlling magnets (as 67, Fig. 9) on pneumatic 92, 93, 94 and 95.

Referring now to the upper part of Fig. 1, I have indicated the usual manner in which the manually operated keys K, are provided with contact elements, as 96, to engage contact elements 97, with circuit wires, as 98, running, respectively, from said keys to the several contact elements 80', on bar 80, while said fixed contact elements 97 are connected in a circuit 99 running to the brush 56 on the generator 53. Also indicated on Fig. 1, is a second manual designated 100, and a third manual designated 101, only fractional parts being shown to indicate the arrangement. Controlled by the keys of the second manual 100, are contact elements at 100', connected in circuits 102, from said keys to the respective contact elements 85' on bar 85, and circuits 103 and 55 to brush 56. Controlled by the keys of the third manual 101, are contact elements at 101', connected by circuit 104, from said keys, to the respective elements 86', on bar 86, and by wires 105 into circuit 103. Return circuit wires, designated 106 and 107, connect with the return wire 108 from the opposite brush 109 of the generator 53.

Electrically operated stop tablet devices 110, are provided for each of the contacts on the bars 81, 82, 83, 84 and 87. One of these mechanisms is shown in enlarged view in Fig. 5, and comprises a box or case 110, with two electromagnets 111 and 111', and a pivoted arm 112, on the outer end of which is a tablet 113, usually manipulated manually. On the inner end of said arm 112 is a curved armature 114, controlled by said electromagnets 111 and 111'. Said armature 114 carries a contact member 115, which moves into and out of engagement with a contact element 116, establishing a circuit through the wire 116', the contact member 115, wire 117, and the terminal 118, which is connected through circuit wire 118' with the generator brush 109. Circuit wire 116' is connected to the usual electrically operated pneumatic switch in the organ chamber, which causes a set of sounding devices to become operable by means of the keys of one of the manuals. Magnet 111 has one of its terminal wires 119 extended out through terminal 119'. The other ends of the magnet wires, designated 120, 120, are connected to the metal part of the box 110'. Terminal 121 is also connected with said metal box 110', and extends to generator brush 109, through wire 108. The wires 119', connect with contact members 81', 83', and 87^a, 87^b and 87^c, respectively. The terminal wire 122, from the magnet 111', connects through wire 122', to contact members 82', 84' and 87^d.

Referring to Figs. 2, 3 and 4, I will describe in detail the mechanism for controlling the swell shutters of the organ chamber. A box 123, has therein a vacuum chamber 124, and two valve chambers 125, 125, with a valve stem 126 for each, each provided with valves 126^a and 126^b, the lower ends of said valve stems 126 resting upon pouches 127, over air pockets, as 128, connected to holes 28 and 29 of the tracker bar 11, through tubes 35, Fig. 1. The chamber 124 is maintained in partial vacuum through pipe connection 129, in the usual manner, while valve chambers 125, 125, are connected through ports, as 130, with bellows 131 and 132, there being an adjustment screw as 133, to regulate the size of port 130 of bellows 131. The movable member of each bellows is provided with a contact blade, as 134, which successively contacts with a series of terminals designated 135, and which are connected through wires 136, respectively, to the magnets operating the pneumatics, as 137, which operate the swell shutters 138, 138, as indicated in the lower left hand corner of Fig. 1.

The mechanisms described are mostly known in pipe organ construction and in self-player piano construction and is only here shown and described sufficiently to enable those versed in the art to understand my invention, which in its embodiment herein, is contained in the construction and arrangement of the switch board shown in the upper part of Fig. 1, where the various circuits can be made to perform additional functions to those usually performed by said circuits. The switch board is controlled from the usual tracker bar, but through additional holes, such as holes 19 to 26, inclusive, Fig. 6, at one end, and holes 27 to 34, inclusive, at the other end of said tracker bar.

Referring to Fig. 12, showing a fragmentary portion of a music roll with my invention applied thereto, and assuming that the paper is traveling in the direction indicated by the arrow over the tracker bar, and that the first row of perforations, designated O, through the fixed member 75 and contact 80', are normal note playing perforations, on manual 13, as said roll advances, the row of perforations N', causes the switch mechanism to operate to break the contacts between contacts 80' and their respective fixed bars 72 to 79, at the same time making contacts 80^a, 80^b, 80^c, and 80^d, with fixed members 76, 77, 78 and 79. Perforations N², in conjunction with N', cause switch bar 81 to move, thereby making contact between 81' and bars 72 to 75. This causes the next perforations O, through contact 81', to depress a stop tablet 113. Perforations N³, in conjunction with perforations N', causes the next perforations O, through contact member 82', to raise said stop tablet 113. This stop tablet controls notes on manual 13. Similarly, perforations N⁴, in con-

junction with N' , causes stop tablet 113, on manual 14, to be depressed, and N^s causes the next perforations O to raise said stop tablet 113.

Perforation N^s , in conjunction with N' , makes its corresponding perforations O , to function to depress a stop tablet 113 on manual 12. Perforation N^s , in conjunction with N' , causes perforations O' to lift all of the 16 stop tablets 113 which controls the notes on manual 12. Perforations N^s causes the operation of movable switch bar 85 and makes perforations O , through one of the contacts 85', with fixed bar 75, to play a note on manual 14, as well as its original function of playing a note on manual 13. Similarly, perforation N^s , in conjunction with perforation N^s , causes perforations O to play on manuals 12, 13 and 14. The next perforation N^s causes perforation O to play a note on manuals 13 and 12. The next perforations N' and N^s , cause perforations O to play a note on manual 12 only. Perforations N' , N^s and N^s , control mechanisms which cause perforations O to play 25 notes on manuals 12 and 14.

Thus it will be seen that with my invention and additional perforations and combinations thereof, I am able to manipulate the various stop tablets automatically and individually, as well as to play notes on one or all of the three manuals. This, I believe, has never been done before.

Referring to Fig. 13, which shows a fragmentary section of a piano roll, I have added 35 perforations O^2 , N^{10} and N^{12} , in advance of the ordinary note playing perforations. Perforations O^2 , in conjunction with perforations N^{10} and N^{11} , control mechanisms which cause the cancellation or lifting of all stops or tablets on manual 13, these perforations all being 40 in one section. The next group of perforations, O^2 , in conjunction with the next perforations N^{12} and N^{11} , control mechanisms which cause the corresponding three tablets 45 on manual 13 to be depressed. This sets up the desired stop tablet combination for the approaching music perforations. The reason I have shown the cancellation group of perforations O^2 , is for the purpose of clearing 50 the stop tablet board in case any of the stop tablets were depressed prior to starting the roll. The set up for a second and third section of the tracker bar is not shown in this figure, as it is only illustrative of what can be 55 done with my invention.

In Fig. 14, which is a specially prepared roll, I have indicated the three sections thereon, corresponding to the three sections of the tracker bar, as well as two of the manuals and 60 pedal section of the organ. From the foregoing description of the mechanisms and the showing as to how various stop tablets can be depressed or raised, it is not deemed necessary to describe this figure in detail. It will 65 be seen, however, that the operation of each

section can be alternated, thereby permitting the music to continue without interruption, one or more of the manuals playing, while the stop tablets for the pedal section are being operated. Also that one manual and pedal 70 section can be operating while the stop tablets for another manual are being operated.

The use and operation of my invention may be briefly described as follows:

As the music roll moves over the tracker bar 75 11, the perforations in the roll register with the holes in the tracker bar in the usual manner, admitting air at atmospheric pressure through the holes which are opened and through the tubes 35, passageways 49, into the air pockets 48. This creates pressure against the diaphragm 47, causing it to lift the movable switch contact 46 against the contact member 45, and establishing a circuit which includes one of the vertical parallel 80 members 72 to 79. It is assumed that the particular hole in the tracker bar is within the note playing range 16, 17 or 18 of the tracker bar. Under present systems, these circuits thus established go directly to the respective 85 keys, as indicated in the upper left hand corner of Fig. 1, where the keys are designated K.

By my invention, I have provided the vertical parallel bars 72 to 79, inclusive, and have also provided the movable horizontal 90 switch members 80 to 87, and I use these not only to continue the circuits as ordinarily required, using horizontal member 80, shown in its normal position, as a part of the circuit, but by means of additional holes in the tracker bar and in the music sheet, as before referred to, I am able to establish additional 95 circuits for operating other electrically controlled mechanism within the organ, and particularly the automatic control of the stop 100 tablets such as 113.

I will now describe how this is accomplished by means of these additional features, which really constitute the heart of my invention.

Referring to Fig. 1, and assuming that a particular hole in the tracker bar 11, which opens passageway 37 to the pouch box 44 and through one of the air pockets 48, is operating and closing the switch elements 45 and 110 46 in circuit 37, which includes vertical member 74, and one of contact members 80', on movable bar 80, to a corresponding key contact on a predetermined manual, it will be seen that this connection will accomplish the 115 same purpose as though the key were manually operated. This is the normal function under the control of this particular tracker bar hole, as found in present self-playing apparatus, with the exception that I interpose in the circuit to the key a vertical bar 74, a horizontal switch bar 80 and one of its 120 contact elements 80', instead of running said circuit directly to the key contact.

Taking for illustration tracker bar hole 22, 125

which is one of the new or additional holes added to make possible my invention, and which controls the operation of pneumatic 61, which in turn moves bar 80, and thereby 5 disengages contacts 80' from their respective vertical parallel members and breaks the circuit established by hole 37. This pneumatic 61, also brings into engagement contact members 80^a, 80^b, 80^c and 80^d with vertical parallel members 76, 77, 78 and 79. These contact members 80^a, 80^b, 80^c and 80^d are connected, respectively, to pneumatics 92, 93, 94 and 95. They also operate to move horizontal switch members 84, 83, 82 and 81, respectively. Thus it will be seen that if in conjunction with holes 37 and 22, hole 42 is opened, a circuit is established through 42', vertical member 79, contact 80^d, to electrically operated pneumatic 95. This pneumatic 20 causes the operation of the movable horizontal member 81, bringing into engagement contact members 81' with their respective vertical members, one of which corresponds to vertical member 74, thereby completing a circuit which causes the depression of one of the stop tablets 113, in the manner indicated in Fig. 5.

Supposing that hole 37 remains open, and also hole 22, and in conjunction with these 30 two holes, hole 41 is opened, it will be seen that by a similar process the same stop tablet will be made to lift through a circuit established by one of contact members 82' on movable switch member 82. Similarly it will be seen that if in conjunction with holes 37 and 22, hole 40, is opened, the stop tablet 113, shown directly to the left hand of movable switch member 83, will be depressed. It will be lifted, if in conjunction with holes 37 and 40, 22, hole 39 is opened to establish a circuit through 39' to vertical member 76, and one of contact members 84'. This shows five distinct purposes for which hole 37 can be used. In addition to these, let us suppose that hole 45 37 is open and hole 21 is opened, through circuit 21', electrically operated pneumatic 60 moves switch member 85, and causes contact members 85' to make contact with their respective vertical members and a circuit is established to one of the keys 100, of manual 13. If in conjunction with holes 37 and 21, hole 22 is opened, thereby interrupting contacts 80', it will be clearly seen that only the key 100, on manual 13, will be affected. If, 50 however, it is desired to have the same note play on both of the manuals, only two holes 37 and 21 are necessary. It will also be seen that if hole 20 is opened in conjunction with hole 37, by a similar process, key 101, on manual 14, is affected by said hole 37. The same note can be made to play on one each of keys 96, 100 and 101, by opening holes 20 and 21 in conjunction with hole 37.

Circuit breakers 86^a are shown on movable switch members 86, which prevent the oper-

ation of pneumatics 81, 82, 83 and 84, thereby preventing the depressing or raising of the stop tablets, while switch 86 is in operation. This gives the playing range of manual 14 four notes more than manual 13, and equal to manual 12. Hole 19 causes the operation 70 of movable switch member 87, through circuit 19' and electrically operated pneumatic 58. It will be clearly seen in the drawing that contact members 87^a, 87^b and 87^c cause 75 the stop tablets shown directly to the left to be depressed, according as their respective circuits are completed. It is also shown that in conjunction with hole 19, if hole 38 is opened, a circuit is established to all of the lower contacts of said stop tablets 113, which causes them to be raised simultaneously.

I claim:

1. In self-player mechanism for pipe organs, means for automatically operating stop tablets and swell shutters, said means including in combination, pneumatic means for operating an electric switch, said means being adapted to be controlled by perforated sheet, an electric switch to be operated, a circuit including said switch, magnetic means included in said circuit to be energized therefrom, mechanism controlled by said magnetic means including a switch member having a plurality of contact elements for making and breaking a plurality of circuits simultaneously, circuits therefor, stop tablets adapted to be electrically operated from said circuits and swell shutters adapted to be electrically operated from said circuits. 85

2. In self-player mechanism for pipe organs using tracker bar and perforated music sheets, mechanism for automatically and individually operating stop tablets and moving swell shutters, said mechanism including in combination with electrically operated stop tablets and electrically moved swell shutters, circuits therefor, fixed switch members forming portions of certain circuits, movable switch members having contact elements connected with certain circuit wires, means for selectively moving said movable switch members to make and break controlling circuits for said stop tablets and said swell shutters, said means being adapted to be controlled 105 in its operation by marginal perforations in said music sheet, said marginal perforations simultaneously cooperating with regular note playing perforations to effect said control. 110

3. In self-player mechanism for pipe organs using tracker bar and perforated music sheets, means for automatically and individually operating the stop tablets of the organ and the swell shutters thereof, said means being controlled from the perforated music sheet moving over said tracker bar, marginal perforations in said music sheet adapted in combination with the note playing perfora- 125 130

tions in said music sheet, to cause said note playing perforations to actuate said means for operating said stop tablets and said swell shutters.

5 Signed at Los Angeles, Los Angeles County, California, this 19th day of September, 1928.
